US00D554632S

(12) **United States Design Patent** (10) **Patent No.:** **US D554,632 S**
Woodley et al. (45) **Date of Patent:** **** Nov. 6, 2007**

(54) **USER INTERFACE**

(75) Inventors: **Nicholas Woodley**, London (GB);
Ignacio Germade, Oxford (GB);
Nicholas A. Jinkinson, Reading (GB)

(73) Assignee: **Motorola, Inc.**, Schaumburg, IL (US)

(**) Term: **14 Years**

(21) Appl. No.: **29/275,330**

(22) Filed: **Dec. 21, 2006**

(51) **LOC (8) Cl.** **14-03**

(52) **U.S. Cl.** **D14/247**; D14/248

(58) **Field of Classification Search** D14/137–138,
D14/147–148, 156, 218, 247–248, 341–347,
D14/496, 390, 399; D16/208; D21/329,
D21/331, 333, 517; 348/14.01–14.02; 361/814;
379/433.01–433.13; 455/556.1–556.2, 575.1,
455/575.3, 575.4, 566, 90.3; D13/164, 168;
439/165
